SUPPORTING FRAME FOR FOOD GRINDERS
AND THE LIKE

Albert H. Taylor, Long Beach, Calif.

Application September 26, 1947, Serial No. 776,370

2 Claims. (Cl. 248—226)

1

This invention relates to a supporting frame for food grinders and the like, which is adapted to be mounted in a kitchen sink or laundry tray, and is provided with means to which a food grinder or the like can be clamped, whereby the food juices and the like normally running from the grinder fall into the sink or tray, and can be easily disposed of.

An object of my invention is to provide a novel supporting tray for food grinders and the like which can be quickly and easily clamped in a kitchen sink or laundry tray, the walls of the sink or tray tapering as is usual in structures of this type.

Another object is to provide a novel supporting frame of the character stated, which can be quickly, rigidly mounted in a sink or tray, and adapts itself to sinks or trays of different dimensions, or different wall tapers.

A feature of my invention is to provide a novel supporting frame of the character stated, which can be quickly mounted or removed as desired, and also which is simple in construction and simple to operate.

Other objects, advantages and features of invention may appear from the accompanying drawing, the subjoined detailed description and the appended claims.

In the drawing:

Figure 1 is a perspective view of my supporting frame mounted in a sink.

Figure 2 is a side elevation of my supporting frame with parts broken away to show interior construction.

Figure 3 is a fragmentary sectional view taken on line 3—3 of Figure 2.

Figure 4 is a fragmentary sectional view taken on line 4—4 of Figure 2.

Figure 5 is an end view taken in the direction of the arrow 5—5 in Figure 2.

Figure 6 is a fragmentary sectional view taken on line 6—6 of Figure 2.

Referring more particularly to the drawing, my supporting frame 1, is substantially rectangular in shape, and consists of two arms 2 and 3. A headpiece 4, extends across the top of the arms 2 and 3, and this headpiece is preferably channel shaped. The arm 2, is attached to the headpiece 4, by means of the bolt 5, onto which the thumbnut 6, screws, thus mounting the arm in position and also permitting a hinging movement if necessary. The arm 3, is similarly attached to the headpiece 4, by the bolt 7, which extends through the headpiece, and through the upper end of the arm, and a thumbscrew 8,

5 screws onto this bolt thus clamping the arm in position relative to the headpiece.

A wooden block 9, may be mounted in the headpiece 4, and serves as a bearing member for the clamping screw of the food grinder, or the like, which is mounted on top of the headpiece 4. At the lower end of the arms 2 and 3, I provide an extension member consisting of a threaded rod 10, and a sleeve 11. A wheel 12, screws onto the rod 10, and the movement of this wheel will expand or contract the lower ends of the arms 2 and 3. A pressure foot 13, is mounted on the lower end of the arm 2, and a similar pressure foot 14, is mounted on the lower end of the arm 3. The foot 13, and the rod 10, are held in assembled position by the bolt 15, onto which a thumbscrew 16, is threaded. Similarly, the foot 14, and the sleeve 11, are mounted on the lower end of the arm 3, by the bolt 17, onto which the thumbnut 18, is threaded.

The foot 13, is preferably provided with a rubber or plastic surface 19, and a foot 14, is similarly provided with a pad or surfacing 20. This prevents the feet from slipping when mounted in the sink or tub. The sink or tub 21, usually has tapered sides and the feet 13 and 14, can tilt to accommodate the slope of the sides. A finger 22, may be mounted on the head 4, for the purpose of supporting a bag or container when draining certain food products. In mounting my supporting frame in a sink or tub, the rod 10, and sleeve 11, are extended by the wheel 12, thus causing the feet 13 and 14, to press tightly against the walls of the sink or tray, and I thus provide a very rigid frame which will not tilt when in use.

Having described my invention, I claim:

1. A supporting frame for food grinders and the like, comprising a pair of arms, a headpiece, a bolt extending through each of the arms and the headpiece, a pressure foot on the lower end of each arm, and a bolt extending through each arm, and each pressure foot, and extensible means mounted on the lower end of each arm, whereby the pressure feet are urged outwardly, said extensible means including a rod mounted on one of said arms, a sleeve mounted on the other arm, and a nut threaded on said rod and bearing against said sleeve.
2. A supporting frame for food grinders and the like, comprising a pair of arms, a horizontal headpiece, extending between said arms, said headpiece being channelled shape, a bolt extending through the upper end of each of the arms and through the headpiece, a pressure foot on

the lower end of each of said arms, a bolt extending through the lower end of each of the arms and through a pressure foot, a rod mounted on one of said arms, a sleeve mounted on the other arm, and a nut threaded on said rod and bearing against said sleeve.
